UNITED STATES PATENT OFFICE

2,015,321

CANOPY FRAME

Hilary S. Shelton, Winston-Salem, N. C.

Application April 19, 1935, Serial No. 17,328

5 Claims. (Cl. 135—4)

This invention relates to a frame for supporting small tents and canopies, one of the objects being to provide a structure of this character which is light but durable and, when not in use, 5 can be folded into a compact bundle so as to facilitate transportation.

A further object is to provide a frame which can be set up quickly and, when properly assembled will provide a rigid support for the canopy cover and walls.

10 A still further object is to combine in the frame construction a new and novel arrangement of ropes or the like which will be drawn taut by the assembly of the frame and constitute both reinforcements and supports.

15 With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

20 In the accompanying drawing the preferred form of the invention has been shown.

In said drawing

25 Figure 1 is a plan view of a canopy constructed in accordance with the present invention, the fabric portions being broken away to show the frame.

Figure 2 is a section on line 2—2 Figure 1.

30 Figure 3 is a perspective view of one of the corner fixtures and a portion of a strut to be used therewith.

35 Figure 4 is a view showing in side elevation one corner portion of the marginal brace.

Figure 5 is a plan view thereof.

40 Figure 6 is a plan view of a portion of the top brace.

Figure 7 is a plan view of the screw carrying plate of the frame.

45 Referring to the figures by characters of reference, 1 designates a central plate or casting having diverging pairs of ears 2 made integral therewith. A central opening 3 is also provided in this plate.

50 Pivottally connected to each pair of ears is the inner member 4 of a strut the outer member of which consists of a length of pipe 5. A dowel 6 is extended from the end of each inner member 4 and is so proportioned as to project into the outer member 5 of the strut whereby the two members 4 and 5 will be held in alinement but 55 detachable from each other.

The outer end of each strut member 5 is adapted to slip onto a pin or dowel 7 extending from the substantially T-shaped fitting 8 which is also formed with a projecting pin 9 extending oppositely to the pin 7 and a pin 10 extending downwardly from the pivot. An opening 11 can be extended through pin 9 for the purpose of receiving a cotter pin 12 or other suitable retaining device.

5 A screw 13 is extended through the opening 3 and is in threaded engagement with the plate 1. This screw has a crank arm 14 or any other suitable device at its lower end whereby the screw can be rotated readily. The upper end of the screw is reduced in size as indicated at 15.

10 Posts 16 which can be formed of pipes or can be of any other suitable construction with tubular upper ends, are employed for supporting the struts 4—5 at a desired height above the surface of the ground, the upper end of each of these 20 posts being adapted to receive detachably one of the pins 10.

15 In connection with the parts thus far described there is used a marginal brace and a top brace. The marginal brace comprises four rings 25 17 connected by ropes 18 or the like so proportioned that when these ropes or other flexible connections are drawn taut, the rings will be regularly spaced apart distances slightly greater than the maximum distances between the fixtures 8.

20 The top brace comprises a plate 19 having a small central opening 20 and secured to this plate are equally spaced ropes 21 or other suitable flexible devices to the outer ends of which are secured rings 22.

25 In assembling the frame thus far described the sections 4 and 5 are assembled and the fixtures 8 are placed on the outer ends of the sections 5. The struts are slightly folded as shown 40 for example by broken lines in Figure 2 so that their outer ends will thus be restricted towards each other. Thereafter the marginal brace is positioned with its rings 17 on the respective pins 9 and after these have been properly located 45 the rings 22 of the top brace are also put on the respective pins 9. The rings are held in place by the pins 12 which are inserted into openings 11 and with the parts thus arranged the struts will be maintained slightly folded as 50 shown by broken lines in Figure 2 because the connections 18 are proportioned to normally prevent maximum extension of the struts. Following the placing of the top and marginal braces the plate 19 is placed on the reduced end 15 of 55

screw 13 and said screw is then fed upwardly by rotating it in the plate 1. Consequently the flexible connections 21 will be drawn taut.

- Continued feeding of the screw 13 will cause 5 the screw to exert a downward thrust on plate 1 so as to move it from the broken line position shown in Figure 2 substantially to the full line position. This will cause the outer ends of the struts to move short distances outwardly so as to 10 push against the rings 17 and draw the connections 18 taut. Thus the one operation of screw 13 will result first in the tightening of the connections 21 and thereafter in the tightening of the connections 18.
- 15 Following the operation described the top frame which is thus set up and reinforced or trussed is mounted on the posts 16 which, as before explained, receive the pins 10. Consequently the top frame will be held at the desired elevation 20 and a top 23 of canvas or other fabric can be placed on the connections 21 while curtains 24 of suitable fabric can then be suspended from the marginal braces 18 by means of snap hooks or the like indicated generally at 25.

- 25 It is to be understood that suitable guys or the like can be used for bracing the tent or canopy after it has been erected.

When it is desired to collapse the structure, cover 23 and the curtain 24 are removed. The 30 pins 10 are lifted from the posts 16 and the screw 13 is then rotated to relieve the tension on the connections 21. This will allow plate 19 to be disengaged from the screw and the rings 22 to be slipped off of pins 9. The struts 35 can then be folded together, sections 5 disengaged from sections 4 and from the rings 17, and the entire structure bundled compactly for convenience in storage and transportation.

The tent or canopy which has been described 40 can be used for various purposes and is advantageous because it lacks a center support and permits the use of vertical walls so that the maximum capacity is provided.

What is claimed is:

- 45 1. A frame for a tent or canopy including a plate, a screw threaded therein, members hingedly connected to the plate and radiating therefrom, an endless detachable connection between the outer ends of the members, and a detachable connection between the outer ends of the members and the screw, said screw being rotatable in the plate to place all of the connecting members under tension.
- 50 2. In a canopy or tent, a frame including a plate, a screw mounted therein, members hingedly connected to and radiating from said plate, a marginal brace detachably connecting the outer ends of the members, a top brace detach-

ably connecting the outer ends of said members and the screw, and posts detachably connected to the members, said screw being adjustable to place the top brace under tension and exert a thrust upon the members to shift radially therethrough against the brace thereby to place the marginal brace under tension.

5 3. In a canopy or tent, a frame including a plate, a screw engaging the same and extending therethrough, members hingedly connected to 10 and extending radially from the plate, an endless marginal brace detachably connecting the outer ends of the members and constituting means for holding said members normally in partly folded positions, top braces detachably connecting the screw to the outer ends of the members, and supporting posts detachably connected to the members, said screw constituting means for thrusting the top braces and the plate in opposite directions respectively thereby to 20 place the top braces under tension and to exert an unfolding action through the plate upon the members to place the marginal brace under tension.

4. In a canopy or tent, a top frame including a 25 plate, members hingedly connected to and radiating from the plate, each member comprising detachably connected normally alining sections, a fitting detachably connected to the outer end of each member and having outwardly and downwardly extending pins, a marginal brace including flexibly connected rings detachably engaging the outwardly extended pins, a top brace including a central element, rings for engaging the outwardly extending pins, connections between 35 said element and rings, posts detachably engaging the downwardly extending pins, said marginal brace constituting means for holding the members normally with their inner or hinged ends above the level of their outer ends, and 40 a screw detachably and adjustably connecting the plate and the top brace element for moving them from each other thereby to successively place the top brace under tension and lower the inner ends of the members to place the marginal 45 brace under tension.

5. In a tent or canopy, a plate, struts hingedly connected thereto, a marginal brace detachably engaging the outer ends of the struts for holding the struts partly folded with their inner ends 50 and the plate above the level of the outer ends of the struts, a top brace connecting the outer ends of the struts, and a screw detachably and adjustably engaging the plate and top brace for shifting them apart, thereby to successively place 55 the top brace under tension and shift the struts and plate to place marginal brace under tension.

HILARY S. SHELTON,
